CENTRIFUGAL CASTING MACHINE

Harold Andrews, Halesowen, England

Application January 11, 1943, Serial No. 472,026
In Great Britain August 1, 1941

3 Claims. (Cl. 22—65)

This invention relates to improvements in centrifugal casting machines for the centrifugal casting of articles such as cylinder liner castings, piston-ring pots or any similar articles.

In casting such articles some form of end plate or ring must be secured against the end of the mould during the casting operation to retain the molten metal and this plate or ring must be readily removable at the end of the operation to allow the casting to be withdrawn.

In U. S. Patent No. 2,023,562 there is described a centrifugal casting machine in which an end plate or ring for a mould is so mounted that it is capable of moving axially relative to the mould and of swinging into and out of alignment with the end of the mould, the ring being drawn mechanically against the end of the mould during a casting operation and being moved axially away from the mould and swung up or down or to one side at the end of the operation to allow the casting to be removed in an axial direction from the mould.

According to my present invention power-operated means are provided in such a machine for actuating the end ring and limiting mechanism is incorporated so that in one limiting position of the power means the end ring is supported in alignment with the end of the mould while in another limiting position the end ring is supported in an angularly displaced position in which it is out of the path of the casting as the casting is being withdrawn from the mould. Thus the operator is relieved of all manual labour in the operation of the end ring and accurate positioning of the end plate is automatically ensured without calling for the exercise of skill or control by the operator.

One preferred practical design of centrifugal casting machine embodying my invention is illustrated by way of example in the accompanying drawings in which:

Figure 1 is a plan of the machine partly in section.

Figure 2 is a side elevation partly in section.

Figure 3 is a side elevation of the front part of the mechanism for raising and lowering the end ring.

Figure 4 is a plan of the mechanism for raising and lowering the end ring.

The machine itself need only be described briefly as it is similar in general construction to that described in U. S. patent specification No. 2,023,562 referred to above.

A hollow main shaft 10 rotatable about a horizontal axis is mounted in heavy spaced roller

journal bearings 11 and is adapted to be driven by an electric motor through a belt running over a pulley 12 on the shaft. A face-plate 13 on the forward end of the shaft has secured to it a number of forwardly projecting arms 14 forming a carrier adapted to carry a readily interchangeable mould indicated in dotted lines at 15.

During the casting operation the front end of the mould is partially closed by an end ring 16 carried by a pair of arms 17 pivoted at their rear ends by pins 18 on slides 19.

The rear end of each slide enters a spring box 20 on a crosshead 21 and a compression spring 22 is arranged between the front end of the box and a collar 23 on the rear end of the slide. This arrangement allows the end ring to yield under axial expansion of the mould. The crosshead 21 is secured to the front end of a tubular sleeve 24 which extends axially through the shaft 10 and is axially movable therein to draw the end plate against and move it away from the front end of the mould. In the operative position of the end ring shown in dotted lines in Figure 2 the ring is axial alignment with and is held against the end 25 of the mould and is positively located by the engagement of bushed holes 25 in the end ring with the reduced ends 26 of rods 27 extending forwardly from the face plate 13.

When the casting is finished the crosshead 21 is advanced by axial movement of the sleeve 24 which disengages the end ring from the rods 27 and disengages brackets 28 on the arms 17 from slides 29 carried by the face plate. The end ring can swing down into the position shown in full lines in Figure 2 in which it is clear of the end of the mould so that the casting can be withdrawn. The end ring when released from the mould is adapted to be supported and moved up into the operative position again by a yoke formed by a cross-member 30 and a pair of arms 31 pivoted on brackets 32 extending forwardly from the frame of the machine. This yoke is moved angularly by a link 33 pivotally connected to the centre of the yoke and to a longitudinally movable rod 34 below and parallel to the main shaft.

Ejection of the casting is effected by an ejector 35 on the forward end of a plunger 36 co-axial with and axially movable in the sleeve 24.

A collar on the rear end of the sleeve 24 is rotatably anchored by means of a bearing 37 in a transverse crosshead 38 which is held against angular movement by means of a lug on the crosshead engaging slidably with a fixed rod 39. Internally screw-threaded nut members 40 secured in the crosshead adjacent each end engage with

parallel screw-threaded spindles 41 which are geared together by a chain connecting the sprockets 42. Thus rotation of the spindles 41 moves the crosshead and the sleeve 24 axially to draw the end plate against or move it way from the end of the mould.

The rear end of the plunger 36 which extends beyond that of the sleeve is similarly rotatably anchored by means of a bearing 43 in a cross-head 44. The bearing is mounted on a short collar or sleeve 45 which has a limited sliding movement on the plunger against the action of a spring 46 to allow for expansion.

Nut members 47 anchored in the ends of the crosshead engage with parallel screwed spindles 48 which are geared together by a chain connecting sprockets 49 so that rotation of the spindles 48 moves the crosshead and the plungers 36 to advance and retract the ejector.

The spindles 41 and 48 are adapted to be coupled to and rotated by mechanism arranged at one side of the machine and actuated or controlled from the front end of the machine but this mechanism forms the subject of a co-pending Patent Application and need not be described here.

Reverting now to the mechanism for raising and lowering the end ring 16 which is the subject of this application, the rod 34 which is slidably supported in guides in the frame of the machine below and parallel to the main shaft is screw-threaded at its rear end which works through a rotatably anchored nut member 71. A sprocket 72 secured to the nut member is coupled by a chain to a sprocket 73 on the shaft of a reversible electric motor 74 mounted at one side of the machine so that the motor rotates the nut member in either direction to advance and retract the rod 34 and to rock the yoke and raise and lower the end ring.

The starting of the motor is conveniently effected by a push-button or other switch adjacent the front end of the machine while it is stopped automatically by switches 75, 76 adapted to be tripped by collars 77, 78 adjustably mounted on the rod 34. These collars are set in such positions that when the motor is advancing the rod 34 to raise the end ring it is stopped when the end ring is in exact alignment with the end of the mould and when the motor is retracting the rod to lower the end ring it is stopped when the end ring is sufficiently clear of the end of the mould to allow the casting to be withdrawn.

After the motor is stopped at the end of the raising movement of the end ring the end ring is drawn against the end of the mould by the mechanism described above and is positively located so that the yoke can then be lowered and the main shaft is put into motion and the molten iron introduced into the mould. The yoke is then brought up into a position to support the end ring which is moved axially away from the end of the mould and out of engagement with its locating means and the motor 74 is reversely energised again to lower the end ring after which the casting is ejected and the cycle of operations repeated.

The motor 74 is fitted with an automatic magnetic brake 79 which is held off while the motor is energised but comes into action immediately

the motor is de-energised to bring the moving parts rapidly to rest.

The collar 78 may also be arranged to control a switch 80 in the circuit of a motor for driving the main shaft so that this motor cannot be energised until the yoke has been lowered again after the end ring has been raised and drawn against the end of the mould.

Where the mechanism for moving the end ring axially towards and away from the end of the mould is actuated by a motor this motor may be energised automatically following the de-energising of the motor 74, a time lag being introduced by means of escapement or dash-pot mechanism.

I claim:

1. A centrifugal casting machine comprising a rotatable main shaft, a mould carrier mounted on the front end of the shaft, an end ring for closing the front end of the mould during casting, said ring being movable towards and away from the end of the mould and being capable of swinging out of alignment with the end of the mould, means for moving the end ring into and out of alignment with the end of the mould, a motor for driving said means, a manually operated switch for energising the motor, a switch for de-energising the motor, means for automatically operating the latter switch when the end ring reaches a limiting position, and a magnetic brake automatically coming into operation to bring the moving parts to rest when the motor is de-energised.

2. A centrifugal casting machine comprising a rotatable main shaft, a mould carrier mounted on the front end of the shaft, an end ring for closing the front end of the mould during casting, said ring being movable towards and away from the end of the mould and being capable of swinging out of alignment with the end of the mould, a yoke pivotally mounted on the machine to rock about a horizontal axis and adapted to engage and support the end ring, a rod axially movable and parallel to the main shaft, a link connecting the forward end of the rod to the yoke, screw-and-nut mechanism for moving the rod axially, an electric motor for driving said screw-and-nut mechanism, a manually operated switch for energising said motor, switches for de-energising said motor, and collars adjustably mounted on the axially movable rod for operating the latter switches as the yoke and end ring reach limiting positions.

3. A centrifugal casting machine comprising a rotatable main shaft, a main motor for driving said shaft, a mould carrier mounted on the front end of the shaft, an end ring for closing the front end of the mould during casting, said ring being movable towards and away from the end of the mould and being capable of swinging out of alignment with the end of the mould, means including a longitudinally movable rod for moving said end ring into and out of alignment with the end of the mould, a motor for driving said means, a manually operated switch for energising said motor, mechanically operated switches for de-energising said motor, adjustable collars on the axially movable rod for actuating said switches in accordance with the position of the end ring, and a switch in the circuit of the main motor actuated by one of said collars.

HAROLD ANDREWS.
